UNITED STATES PATENT OFFICE

THOMAS E. MURRAY, JR., OF BROOKLYN, NEW YORK, ASSIGNOR TO MURRAY RADIATOR CORPORATION, A CORPORATION OF NEW YORK

RADIATOR

Application filed July 16, 1929. Serial No. 378,653.

In certain previous applications, Serial Nos. 310,959, filed October 8th, 1928, and 345,985, filed March 11, 1929; I have described a certain improved radiator and method of production. The present application is a continuation in part of No. 210,959, covering the radiators and showing also certain modifications; the earlier application is limited to claims for the method of production. Apparatuses of this sort are used generally for heating the air of a room, or they may be used for cooling the air by circulating cold brine or the like through them.

The accompanying drawings illustrate embodiments of the invention.

Fig. 1 is a plan and Fig. 2 an elevation of a radiator;

Figs. 3 and 4 are horizontal sections through a tube and a joint respectively;

Fig. 5 is a vertical transverse section;

Fig. 6 is a section similar to Fig. 4 illustrating a modification;

Figs. 7 and 8 are similar sections illustrating successive stages in the production of an alternative design;

Figs. 9 and 10 are modifications of Figs. 6 and 8 respectively;

Fig. 11 is a view similar to Fig. 3 showing a modification;

Fig. 12 is a view similar to Fig. 8 showing a modification thereof;

Fig. 13 is a perspective view showing a further modification;

Fig. 14 is a horizontal section of still another modification.

The heating element is a tube 1 for conveying steam or other heating medium, preferably made of thin copper or aluminum for high conductivity.

Applied to one or, preferably to both of the opposite sides of the pipe are extended area structures, preferably also of thin sheet copper or aluminum, corrugated in the manner shown. The extended area structure at each side may be made of a single sheet extending the length of the radiator or of two or more sections making up the total length. The inward corrugations have vertical longitudinal portions 2 which are bent out at intervals to form recessed portions 3 embracing the

pipes 1. At both sides of the portion 2 the sheet extends outward in portions 4 which diverge until they reach the outer sides of the tube 1. Each outward corrugation comprises what we may call an inner segment composed of two transverse portions 4, and an outer segment which is widely rounded at both sides 5 and projecting in the longitudinal direction beyond the intermediate connecting portions 6. Thus the transverse portions of each outward corrugation converge towards the heating element to about the point of engagement therewith and then diverge to the edges of the inner longitudinal portion 2.

This shape has certain advantages which will be appreciated by comparison with the shape shown for example in Phelps Patent No. 1,716,459 June 11, 1929, and employing the same quantity of sheet metal and the same area. Instead of rather narrow and angular vertical flues and passages, the new shape presents widely rounded spaces which permit an easier flow of air through them. The complete width of the radiator is materially reduced.

In the particular case illustrated, there is a reduction of about twenty-five per cent in the floor space occupied by the radiator. In the new shape, each of the corrugations is stiffer. The rounded sides 5 projecting beyond the connecting portion 6 project the latter from accidental blows and deformation. The appearance of the complete radiator is also considerably improved.

The corrugated sheets may be applied to the steam pipe or other heating element by any usual or suitable means. According to the drawing, straps 8, preferably of steel, are provided with recessed portions 9 embracing the portions 3 of the sheets and clamping them together about the pipe 1; the opposite straps being united above and below the tubes by welds 10 passing through the portions 2 of the sheets. If we call the space 11 within the outward corrugations "inside flues" and the spaces 12 "outside flues", it will be observed that the diverging parts 5 of the sheet serve to substantially or approximately close

these outside flues and thus to increase the draft through them.

The narrowest part of these outside flues is narrower than the straps 9. The straps 5 may be introduced by assembling the parts while the sheets are shaped with wider spaces between the outward corrugations, as with the shape in Fig. 7, and subsequently reshaping the sheets.

10 The spaces at the outer side of the outside flues may be further narrowed by bringing the sides closer together. In Fig. 6, for example, the sides 5^a are brought nearly together across the outside flues 12. They may be brought into actual contact, though this would not substantially change the effect as compared with the leaving of a narrow slit. See 5^b, Fig. 9.

15 In Fig. 8 the corrugations are shown of a somewhat different shape. The sheets are applied to the tube 1 in the form shown in Fig. 7 with sides having parallel portions 13 and outwardly converging portions 14 connected at their edges by a channel-shaped portion 15. After assembling the parts in this shape the corrugations are re-shaped by bending them inward as shown in Fig. 8. This leaves each of the inside flues 11 bounded by a protecting rib 15^a on the outside with 20 diverging outer walls 14^a and converging inner walls 13^a, formed from the parts 15, 14 and 13 respectively.

25 The ribs 15^a serve the same purpose of protecting the face of the radiator from accidental injury which is served by the protecting portions 5 of Figs. 4 and 6.

30 The outside flues 12 are bounded by sides 13^a which at their outer edges substantially or approximately close the flues (or may be shaped to entirely close them as at 14^b, Fig. 10). This shape has functions similar to those of Figs. 4 and 6. The inside flues 11 constitute wide spaces at the sides of the tube 1 through which spaces the heated air flows 35 freely. The spaces between these wide inside flues bear a comparatively small ratio to the spaces within the inside flues; and these intermediate spaces 12 are also substantially closed so as to constitute flues in 40 which a better draft is maintained than would be the case with open channels.

45 Various other kinds of heating element may be used. For example, the tube may be flattened transversely to occupy less width, or may be a single narrow chamber instead of the successive lengths of tubing illustrated. Or it may be an electric heater; of the strip type, for example.

50 Preferably the extended area structure is united to the heating element, by the welded straps illustrated or in other ways, before reshaping it, though the re-shaping can be effected after the parts are assembled and before they are actually united. And it will be 55 understood that the extended area structure

may be applied to only one side of the heating element as described in certain of said prior applications, though for most uses the radiator will include two such structures applied to opposite sides of the heating element.

70 Or the radiator may be provided with two different designs of extended area structure, one at each side, as in Figs. 11, 12, 13 and 14. Generally, though not necessarily, the deeper and narrower corrugations shown at the upper sides of these figures will be used as the back of the radiator; referring to the horizontal dimension from the center of the pipe to the outer wall of the corrugations as their depth, and referring to the dimension of the corrugations parallel to the length of the pipe as their width. By having the wider individual corrugations at the exposed front we produce a smoother and more attractive appearance and we also secure a better protection from accidental injury as explained above. The deeper and comparatively narrow corrugations at the back permit an easier and more voluminous flow of air and thus facilitate the circulation of the air in the room.

75 The shallower corrugations also may be placed at the back with advantage where economy of space is desired there. In any case it will be observed that there is a considerable economy of space in arranging a given area of sheet metal with the comparatively flat corrugations at one side, although such economy is naturally greater with the flattened corrugations at both sides.

80 In the cases illustrated, the same area is provided by the corrugated metal at both sides. But they may differ in this respect, and various other designs may be used to secure the same function or functions.

85 According to Fig. 11, the front sheet is bent to form parts 5 and 6 and to include flues 11 and 12 the same as in Fig. 3. At the other side however, the sheet is bent to form transverse plates 16 connected by outer longitudinal plates 17, enclosing vertical flues 18 which are closed and 19 which are open at the outer side.

90 Similarly in Fig. 12 the plate at one side is bent to form protecting ribs 15^a, diverging sides 14^a and converging sides 13^a; while the sheet at the other side is bent similarly to that of Fig. 11 to form transverse plates 16 connected in pairs by the outer longitudinal plates 17.

95 In Fig. 13 on one side the sheet is bent to form outer protecting ribs 20 and outer walls 21 which are flat and extend longitudinally and from the edges of which transverse inwardly converging walls 22 form the inward corrugations. The walls 22 are connected in pairs at their inner edges by the portions 2 which are bent out at intervals to embrace the pipe as in the previously described constructions. The other wall is made of a sheet

bent to form transverse sides 16 connected by longitudinal sides 17 as in the previous figures.

Fig. 14 illustrates a construction in which the shallower and wider corrugations at one side are made of a design shown in my co-pending application, Serial No. 345,985, filed March 11th, 1929. A sheet is bent to form transverse walls 23 and the outer wall of each closed flue is bent deeply inward as at 24 to form supplementary corrugations adding considerable stiffness to the structure in the lateral direction. The corrugations at the opposite sides are of the deep type previously described with transverse portions 16 connected in pairs by longitudinal portions 17. These corrugations also may be considerably varied from the specific cases illustrated, and the same is true of the deeper corrugations shown in the other figures, 11, 12 and 13. They may for example be made of the same general type as the corrugations shown at the lower sides of these figures but of different depth or different width therefrom.

Various other modifications may be made by those skilled in the art without departure from the invention as defined in the following claims.

What I claim is:

1. A radiator including in combination a heating element and an extended area structure united thereto consisting of thin sheet metal corrugated in horizontal section, the outer faces of the corrugations having a certain total width and having outwardly projecting portions of less than the full width of such faces.

2. A radiator including in combination a heating element and an extended area structure united thereto consisting of thin sheet metal corrugated in horizontal section, each outward corrugation having an outer portion which is wider than the central portion so as to permit an easy flow of air in contact therewith in the enclosed space.

3. A radiator including in combination a heating element and an extended area structure united thereto and corrugated in horizontal section, the corrugations being in engagement with the heating elements at opposite laterally registering points and the corrugations at one side of the heating element being deeper than those at the other.

4. A radiator including in combination a heating element and an extended area structure united thereto and corrugated in horizontal section, the corrugations being in engagement with the heating elements at opposite laterally registering points and the corrugations at one side being narrower than those at the other.

5. A radiator including in combination a heating element and an extended area structure united thereto and corrugated in hori-

zontal section, the corrugations at both sides having the same length of engagement to the heating element but those at one side being deeper than those at the other.

6. A radiator including in combination a heating element and an extended area structure consisting of corrugated sheet metal applied to the opposite sides of the heating element, the corrugations at one side having outer portions which are of greater width than the spaces between them and the corrugations at the other side having outer portions which are narrower than those of the first-mentioned side.

7. A radiator including in combination a heating element and an extended area structure consisting of corrugated sheet metal applied to the opposite sides of the heating element, the corrugations at one side having outer portions which are wide and flat and extend longitudinally of the radiator and are separated by comparatively narrow spaces and the corrugations of the other side having their outer portions of less width and greater spacing.

8. A radiator including in combination a heating element and an extended area structure consisting of corrugated sheet metal applied to the opposite sides of the heating element, the corrugations at one side having outer portions which are wide and flat, with narrow vertical projecting ribs along the center and which are separated by spaces of less width, and the corrugations at the other side having their outer portions of less width and greater spacing than those of the first-mentioned side.

9. A radiator for heating the air of a room including in combination a heating element and an extended area structure united thereto consisting of thin sheet metal corrugated in horizontal section, the sides of each outward corrugation converging toward the heating element and the outer portions of the corrugations forming a generally flat vertical face of the radiator, the inner portions of the corrugations engaging the heating element at separated points in its length, leaving between them substantial portions of the heating element exposed so as to form with the outer corrugations flue walls for heating the air by contact therewith and for causing an upward draft and circulation thereof.

10. A radiator for heating the air of a room including in combination a heating element and an extended area structure united thereto consisting of thin sheet metal corrugated in horizontal section, the sides of each outward corrugation converging toward the heating element and the outer portions of the corrugations forming a generally flat vertical face of the radiator, the inner portions of the corrugations engaging the heating element at separated points in its

length, leaving between them substantial portions of the heating element exposed so as to form with the outer corrugations flue walls for heating the air by contact therewith and for causing an upward draft and circulation thereof, the outward portions of the successive corrugations being closely adjacent to one another so as to form an outer face which is substantially continuous in the lengthwise direction.

10 11. A radiator for heating the air of a room including in combination a heating element and an extended area structure united thereto consisting of thin sheet metal corrugated in horizontal sections, the inner portions of the corrugations engaging the heating element at separated points in its length, leaving between them substantial portions of the heating element exposed so as to form 15 with the outer corrugations flue walls for heating the air by contact therewith and for causing an upward draft and circulation thereof, each outward corrugation having a 20 point of maximum width from which the sides converge toward the heating element and also toward the outer face of the structure.

25 12. A radiator for heating the air of a room including in combination a heating element and an extended area structure united thereto consisting of thin sheet metal corrugated in horizontal section, the sides of each outward corrugation converging toward the heating element and the outer portions 30 of the corrugations forming a generally flat vertical face of the radiator, the inner portions of the corrugations engaging the heating element at separated points in its length, leaving between them substantial 35 portions of the heating element exposed so as to form with the outer corrugations flue walls for heating the air by contact therewith and for causing an upward draft and circulation thereof, said extended area structure 40 being arranged at the front and back of the heating element and the spaces between adjacent outward corrugations being narrower in the extended area structure at the front than in that at the back.

45 50 In witness whereof, I have hereunto signed my name.

THOMAS E. MURRAY, JR.
